UNITED STATES PATENT OFFICE.

DEMETRIO HELBIG, OF ROME, ITALY.

OXIDATION OF NITROGEN BY MEANS OF ELECTRICITY.

No. 887,326.

Specification of Letters Patent.

Patented May 12, 1908.

Application filed January 23, 1905. Serial No. 242,442.

To all whom it may concern:

Be it known that I, DEMETRIO HELBIG, professor of electrochemistry, residing at Rome, Italy, 39 Panisperna, have invented 5 certain new and useful Improvements in the Oxidation of Nitrogen by Means of Electricity, (for which I have obtained Letters Patent of the Kingdom of Italy, dated August 6, 1904, No. 73,167,) of which the following is a specification.

The object of the present invention is a process of oxidation of atmospheric nitrogen by causing it to pass, only with oxygen or mixed with other gases, through an electric 15 flame (arc) burning between two cooled electrodes and surrounded by certain fireproof materials so that the flame is thereby confined or closed and the gas mixture is thus obliged to pass the whole space filled with 20 the flame.

The materials used for confining the space of the flame are metal oxids, such as the oxids of calcium and magnesium which when heated are capable of ionizing the gases in 25 their vicinity, *i. e.* increasing the electric conductivity of same. The points of the electrodes may equally be surrounded with such materials so that the points extend beyond the said materials. By this arrangement 30 the above said ionizing action is furthermore increased. The principal advantages obtained by the said arrangement are the following:—

(a) The current necessary to feed the electric flame obtained under the above described circumstances needs only a potential of about 300—600 volts, whereby the apparatus is considerably simplified and a great safety is obtained;

(b) The flame burning under the above said conditions is very constant and is not detached even by the passage of a very rapid gas current, so that in the same unity of time and with a given quantity of electric 45 energy consumed in the flame, great quantities of gas mixture may be subjected to the action of the flame;

(c) As the whole of the gas mixture admitted into the apparatus is obliged to pass 50 the zone heated by the electric flame to the temperature of reaction, on the discharge from the apparatus the oxids of nitrogen are obtained diluted with the least possible of unaltered passed gases;

(d) The fact of working with a great quantity of energy in one place and acting on a

great quantity of gas mixture allows of the most advantageous utilization of the energy, losses by irradiation etc. being reduced to a minimum;

(e) The heat conveyed by the gases from the zone of the flame may easily be given up again to the fresh gases fed to the flame, whereby a further economy of energy is realized.

The annexed drawing shows a practical application of the above mentioned principles.

In the said drawings *x* is a block of one of the said materials (f. i. magnesia, lime, etc.), *p*, *p'* are the electrodes the points of which are surrounded with the same materials (*m* Fig. 3) and, if necessary, prevented from melting by liquid cooling in the manner shown. The said electrodes extend through 75 two holes at the sides of block *x*, into a canal *y* passing through the block, and are provided with packing *h*, *h'*. The electric flame is lighted as an ordinary arc, the electrodes being brought into contact and then gradually moved away from each other until only their points extend into the canal *y*, when the flame will fill up the whole transverse section or area of the canal between the electrodes.

The gases to be treated enter the admission tube *a*, pass through tube *b* and then the apparatus *r* bored parallel to *y* and *y'* through the block and enter at *z* the channel *y*, which may be termed a chamber, where they cross 90 the flame, passing then through channel *y'* and are discharged from the apparatus through tube *c*.

From the foregoing it will be seen that when the arc is struck within the chamber, 95 above described, the surfaces of the walls of which chamber are of ionizing material, and during a time when there is present within the chamber some of the gas to be treated that this will be ionized by the electric flame, and that as the length of the arc is increased the ionizing will continue, and that after the arc has been sufficiently lengthened so that the flame passing across the same completely fills the chamber that such flame will intercept the stream of gas flowing through the chamber, since if the stream of gas is flowing through the chamber and a flame is passing across the chamber and filling the space thereof one must intercept the other and the 100 desired results will be accomplished. 105

The heat conveyed by the gases from the

flame is given up to the walls of *y'* and *c* and by the latter to the counter current of fresh gases passing through *b* and *r* so that these gases reach *z* in a pre-heated condition.

5 The purpose of the plates *d* is both to produce tight closure and prevent loss of heat. The mica plate *s* allows the inspection of the flame.

Having now described my said invention 10 and the manner in which the same is to be performed I declare that what I claim as my invention and desire to secure by Letters Patent is:—

1. The art of oxidizing atmospheric nitrogen which consists in passing the gas to be treated through a chamber having the surfaces of its walls of ionizing material, striking an electric arc within the chamber and ionizing the gas therein, and increasing the

length of the arc until the flame passing across 20 the arc fills the chamber and intercepts the stream of gas passing through the same.

2. The art of oxidizing atmospheric nitrogen which consists in passing the gas to be treated through a chamber, the surface walls 25 of which are of magnesium oxid, striking an electric arc within said chamber and ionizing the gas therein and increasing the length of the arc until the arc flame passes across and completely fills the cross section of the 30 chamber.

In testimony whereof I affix my signature in the presence of two witnesses.

DEMETRIO HELBIG.
